UNITED STATES PATENT OFFICE.

FREDERICK C. JOHNSON, OF JERSEY SHORE, PENNSYLVANIA.

MACHINE FOR DRILLING OR BORING.

1,314,669.

Specification of Letters Patent.

Patented Sept. 2, 1919.

Application filed July 11, 1917. Serial No. 179,866.

To all whom it may concern:

Be it known that I, FREDERICK C. JOHNSON, a citizen of the United States, residing at Jersey Shore, in the county of Lycoming and State of Pennsylvania, have invented 5 certain new and useful Improvements in Machines for Drilling or Boring, of which the following is a specification.

The main object of the invention is the provision of a machine for drilling holes in the webs of steel railroad track rails, especially when the rails are in position upon and secured to the ties, the machine being adapted to be operated by a motor velocipede engine 15 such as are commonly used on railroads.

However, the machine may be adapted for operation by manual or other than gas engine power, and used for other and analogous purposes than that specified.

20 The accompanying drawings illustrate an example of the embodiment of the invention especially adapted for operation by a hydrocarbon engine and for use in drilling holes in the webs of steel rails when forming part of a railroad track, the same being constructed and the parts combined according to the best mode of procedure I have so far devised for the purpose.

Figure 1 is a top plan view.

30 Fig. 2 is a side view in elevation with certain parts in section.

Fig. 3 is a cross section of Fig. 2 at line 3—3.

Fig. 4 is a section of Fig. 2 at line 4—4.

35 Fig. 5 is a detailed view of one spindle and the wheels 2 and 6.

The supporting and anchoring frame of the machine comprises two cast or wrought metal bars A A, preferably angular in cross 40 section, united by a plurality of rods B, two in this instance. Each free end carries a hook C which extends over a rail D, as shown. The opposite ends of the bars are preferably united by an integral curved bar

45 E located in a plane below the adjacent or central parts of the bars, and an additional bar or metallic connection F is preferably present, and the bar E has ends G G extended far enough to rest upon the top surfaces of two adjacent cross ties of the roadbed. The crossbar E should extend far enough to receive a foot of the operator for holding the machine firmly in place upon the ties and the bars in engagement with

55 the rail to be drilled. By this construction

the gearing is supported above and out of contact with the roadbed and ballast.

Upon the bars A A are adjustably supported, so they can be relatively moved, two similar castings H H, each casting being provided with slots I I within which the bars A A are located and adjustably held by set or stub bolts J, as indicated. Each casting has two holes K K in the same horizontal plane for the passage of the drill shafts or 60 spindles, and each top edge is provided with a casting L removably secured in position by two threaded set bolts M M. Openings N are formed half in the top edge of each casting and half in the lower part of each 65 casting L within which the two-part power shaft has its bearings.

Upon the inner surface of each casting and surrounding the openings K K are recesses within which are located the ball bearing plates O O each grooved to receive the balls P and support the gearing.

A sheet metal covering Q incloses the gearing between the end castings and it is removably held in position by threaded 75 stub bolts R, as shown. A handle X may be secured to the end castings by bolts V by which the machine can be lifted and carried or moved.

The movable or operative elements are 80 designated as follows: S S are two shafts or spindles, each being threaded at one end with left handed threads T, ten to the inch, the other end having a seat for a drill which is removably held by a set-screw U, 85 and a keyway W extends approximately the entire length of each shaft or spindle.

Upon the spindles are mounted toothed gear wheels 1, 2, 6 and 7. The wheels 1 and 2 have integral keys 10 which enter the key 90 seats or ways in the spindles so the spindles can be moved lengthwise or slide relative to these two wheels. Wheels 6 and 7 are interiorly threaded so the spindles can be moved relatively to these two wheels, not 95 slidingly, but by rotating the wheels. All the wheels have recesses 8 in the vertical sides or surfaces to receive ball bearing plates 9, similar to plates O O, each grooved to hold in place the balls P, as clearly shown.

100 The power transmission shaft is comprised of two parts 11 and 12. The former has a sprocket wheel 13 and a power toothed wheel 3 meshing with wheels 1 and 2. The latter has a toothed gear wheel 5 which 110

meshes with wheels 6 and 7. The latter part 12 is provided with a disk 16 and handle 17 for rotating the disk and wheel 5.

The two parts 11 and 12 of the shaft are 5 united by the ratchet toothed clutch 18, half formed on each of the two wheels 3 and 5 so motion can be transmitted from shaft 11 to shaft 12 by the rotation of the sprocket wheel. The part of the shaft 12 with the 10 wheel 5, disk and handle can be moved rearwardly to disengage the clutch mechanism (made possible by the open space 19) without disengaging the teeth of wheel 5 from the teeth of wheels 6 and 7.

15 Note that the front or driven gear wheels 1 and 2 and the feed wheel 5 have thirty two teeth each, and that the rear or feed wheels 6 and 7 and the wheel 3 have thirty one teeth each. Obviously, by this arrangement both 20 the spindles and drills will be rotated by wheels 3, 1 and 2, and at the same time moved or fed longitudinally by wheels 5, 6 and 7 and through wheels 1 and 2 as the drills penetrate the metal of the web of the 25 steel rail.

In using the machine it is placed between the rails and the bars are hooked over a rail, the rear end of the frame being supported upon two ties.

30 By handle 17 the disk, shaft 12 and wheel 5 are slid rearwardly, disengaging the clutch 18. The disk is then rotated, which turns wheels 5, 6 and 7 and moves the spindles and drills till the drills bear against the web 35 of the rail. The sprocket wheel is then rotated through the medium of a sprocket chain uniting the sprocket wheel with a similar wheel in gear with the shaft of a gas engine carried by a motor velocipede located on the track rails adjacent to the 40 machine.

When the two holes are drilled in the rail the engine is stopped, the disk, shaft 12 and wheel 5 are slid rearwardly and rotated, 45 which action moves the spindles rearwardly and withdraws the drills from the holes in the rail.

Obviously, one hole only can be drilled by removing one of the drills from a spindle. 50 Further, and when desired, the invention may be embodied and used with a single spindle and drill by discarding wheels 1 and 6 or wheels 2 and 7 and one spindle, the operation of the machine remaining substantially the same.

To change the speed of the feed the threads of the spindles and the threads at the interiors of the wheels 6 and 7 may be changed, and also the number of the teeth 60 on the gear wheels be varied to secure the desired result without substantially departing from the principle of the invention.

The gearing may be operated by manual power, using well known devices for the 65 purpose. I have not illustrated the same by

the drawings, inasmuch as such manual power means would be a substantial equivalent of the gas engine power means described.

What I claim is:

1. The combination of a supporting frame; a shaft or spindle threaded at one end and carrying a cutting tool at the opposite end; a driven gear wheel on the spindle suitably supported so as to rotate the spindle but allow longitudinal movement of the spindle relative thereto; a suitably supported second and interiorly threaded feed gear wheel on the threaded part of the spindle; a power shaft formed in two parts, as 11 and 12, united by a clutch mechanism each of said parts carrying a power gear wheel meshing with the gear wheels on the spindle the part 12 of the power shaft with its gear wheel being slideable to disengage the clutch mechanism while still in mesh with the feed gear wheel and having means for rotating said part and gear wheel only to move the spindle longitudinally relative to the driven wheel; and means for receiving energy from a source of energy and transmitting the same through the two power gear wheels to the said feed and driven wheels independent of the spindle; the teeth on said wheels varying in number so that the feed gear wheel will be rotated at a speed different from the speed of the adjacent driven wheel and thus move the spindle longitudinally through the said driven wheel. 90

2. The combination of a supporting frame; two shafts or spindles each threaded at one end and carrying a cutting tool at the opposite end; two driven gear wheels, one on each spindle and suitably supported so as to rotate a spindle but allow longitudinal movement of the spindle relative thereto; two suitably supported and interiorly threaded feed gear wheels, one on the threaded part of each spindle; a power shaft having two power wheels in mesh respectively with the driven and feed gear wheels on the spindles, one power wheel being slideable relative to the two feed gear wheels, but remaining in mesh with them; and means on said power shaft to directly receive energy from a source of energy independent of the spindles; the teeth on said wheels varying in number so that the feed gear wheels will move the spindles longitudinally through the drive gear wheels when the power shaft 110 is rotated. 115

3. The combination of claim 2 when the power shaft is formed in two parts, as 11 and 12 united by a clutch mechanism and the part 12 adapted to be moved with its power wheel 5 to an unclutched position and when rotated impart motion to the feed wheels only. 125

4. The combination of two bars having hook-shaped free ends and united at their op- 130

posite ends; two castings, each having openings for a spindle and a power shaft, and detachably secured to the said two bars; and a spindle carrying a toothed drive wheel and a toothed feed wheel, and a power shaft carrying two power toothed gear wheels, both said spindle and said power shaft being suitably supported by said castings.

5. The combination of two bars having free ends shaped to engage the head of a track rail; two castings, each having openings for two spindles and a power shaft, and

detachably secured to the said bars; two spindles each carrying a drive wheel and a feed wheel, and a power shaft carrying two power gear wheels, located within the openings in the castings; and suitable bearings for said spindles and power shaft. 15

In testimony whereof I affix my signature.

FREDERICK C. JOHNSON.
